United States Patent Office

Des. 217,440
Patented May 5, 1970

217,440

MILK CASE

Howard Hyland McIlvain, Cincinnati, Ohio, assignor to Borden, Inc., New York, N.Y., a corporation of New Jersey

Filed Jan. 15, 1969, Ser. No. 15,365

Term of patent 14 years

Int. Cl. D9—04

U.S. Cl. D9—177

FIG. 1

FIG. 2

FIG. 1 is a front and side perspective view of a milk case showing my new design; and

FIG. 2 is a bottom perspective view thereof showing the sides opposite those shown in FIG. 1.

I claim:

The ornamental design for a milk case, substantially as shown.
